F. LILIENFELD ET AL.

OIL BURNER

Filed March 31, 1926

FIG. 1.

64

Patented Nov. 23, 1926.

1,608,106

UNITED STATES PATENT OFFICE.

FRANK LILIENFELD AND GEORGE S. LOVE, OF SAN FRANCISCO, CALIFORNIA.

OIL BURNER.

Application filed March 31, 1926. Serial No. 98,679.

The present invention relates to oil-burners, and more particularly to that type in which a steam-jet is employed for the disintegration and volatilization of the hydrocarbons, the two thereafter entering the combustion chamber as a vaporized spray.

A primary object of our invention is the provision of means for the thorough incorporation of the oil and steam molecules preliminary to their ejection into the combustion chamber.

In the accompanying drawings, forming a part of this specification:

Figure 1 is a top plan view of our oil-burner, showing the relative arrangement of the oil and steam inlets and their respective control valves, the rotor and the mixing-chamber, parts being broken away for clearness of illustration; and

Figure 2 is a transverse sectional view taken through the burner block, showing the mixing-chamber and the relative arrangement thereto of the steam-inlet, the rotor and the discharge outlet leading to the burner nozzle, the section being indicated by the line 2-2 of Figure 1.

Referring with greater particularity to the drawings, in which a preferred embodiment of our invention has been illustrated, 1 indicates, in a general way, the burner-block 30 having a central bore 2 into which is fitted a pair of oppositely disposed flanged plugs 3 and 4 forming therebetween, and centrally of the block 1, a mixing-chamber 5.

The flanges of the plugs 3 and 4 are secured to the upper and lower faces, respectively, of the block 1 by a plurality of machine screws 6 and 7, and are provided centrally thereof with openings 8 and 9 adapted to receive thrust-bearing members 10 and 11 formed on opposite sides of the rotor 12, the rotor being revolvably supported by means of said bearing-members and supporting-studs 13 and 14 provided with conical ends 15 and 16 adapted to fit within corresponding conical seats formed in the rotor bearing-members.

The steam-inlet pipe 17, leading from the supply source, is tapped into a port 18 in the block 1 and a second 19 is formed in the block at right-angles to the port 18 and communicating therewith, the port 19 being tapped for the reception of a needle-valve 20 having a stem 21 provided with a conical end adapted to seat in the tapered seat 22 formed in a port 23 which communicates

with the port 19 and the chamber 5 of the burner, the port 23 being arranged in axial alignment with the discharge 24 formed oppositely thereto in the block, the said port and exhaust being both substantially tangentially arranged relative to the rotor, as shown in Figure 1.

The oil-supply line 25 is tapped into the block and communicates with a port 26, a second port 27 being formed in the block at right-angles to the port 26 and communicating therewith. A smaller port 28 communicates with the port 27 and the mixing chamber 5, the port 28 having a valve-seat 29 into which the conical end of the valve-stem 30 borne by the oil needle-valve 31 is adapted to seat through which the oil-flow to the chamber 5 is controlled.

The rotor 12 is preferably of cylindrical form, as shown in Figure 2, and is designed to rotate freely upon its bearings within its chamber 5, it being so constructed as to provide a central cylindrical body uniting two oppositely disposed frustum of cone bodies, thus constituting a reduced portion 32 and flared flanges 33 and 34, thereby providing an annular space between these bodies and the central portion of the bore 2 constituting the mixing-chamber 5.

The steam-jet entering the port 23, as regulated by the valve 20, impinges against the peripheral surface of the cylindrical portion 32 of the rotor 12 causing it to rotate at high velocity in the direction of the arrow 90 in Figure 1, while, simultaneously, a jet of oil is sprayed against the rotor from the port 28, through the proper manipulation of the needle-valve 31. The oil as thus sprayed and received by the rotor is given, initially, the impulse and velocity of this member spinning at high velocity and is thrown therefrom through centrifugal action with force against the wall of the bore, from whence it is deflected and borne along at an increasing velocity to be met by the inrushing steam-jet and thoroughly disintegrated thereby and commingled therewith and passed on, as a completely volatilized product, to the discharge-port 24 and thence ejected under high pressure through the burner-tip, or nozzle, 35 into the combustion-chamber, where the intense heat decomposes the steam constituent into its component gases, hydrogen and oxygen, combustion elements greatly increasing the fuel value.

We claim:

1. An oil burner of the character described, comprising means forming a mixing-chamber, a rotor in said chamber, said rotor consisting of a reduced central section having oppositely disposed flanges, means forming adjustable thrust-bearings for said rotor, a valve-controlled steam-port and a valve-controlled oil-port communicating with said chamber at relatively remote points, said steam-port being arranged in tangential relation of said rotor, and a discharge-outlet leading from said chamber in substantially axial alignment with said steam-port.
2. An oil burner comprising a block having a mixing-chamber therein, a rotor in said chamber, adjustable thrust-bearings for said rotor, the said rotor being of substantially cylindrical form, a valve-controlled steam-port and a valve-controlled oil-port in respective communication with said chamber, said steam-port being arranged in tangential relation to the peripheral surface of said rotor and adapted to discharge a steam-jet tangentially thereto against to cause said rotor to spin at high velocity, said oil-port being arranged to communicate with chamber at a point spaced away from said steam-port and adapted to

discharge an oil-jet into said chamber and against said rotor, and a discharge-outlet arranged to communicate with said chamber at a point opposite said steam-port.

3. In an oil burner of the class described, a block forming a burner housing, a bore in said block, flanged plugs in said bore, the said bore and plugs forming a mixing-chamber, a rotor in said chamber carrying thrust-bearing members, said rotor being of substantially cylindrical form and so constructed as to constitute a central cylindrical section uniting oppositely disposed frustoconical bodies, bearing-supports carried by said plugs adapted to engage said rotor bearing-members, valve-controlled means for introducing a steam-jet into said chamber in tangential relation to the peripheral surface of the rotor, a valve-controlled means for introducing an oil-jet into said chamber, and a discharge-outlet carrying a burner-tip communicating with said chamber at a point remote from said steam and oil jets but substantially in axial alignment with said steam-jet.

In testimony whereof we have affixed our signatures.

FRANK LILIENFELD.
GEORGE S. LOVE.
